ADJUSTABLE FULCRUM PLIERS

Filed April 22, 1947

UNITED STATES PATENT OFFICE

2,558,440

ADJUSTABLE FULCRUM PLIERS

Joseph N. Johnson, Oakland, Calif.

Application April 22, 1947, Serial No. 743,002

3 Claims. (Cl. 81—51.3)

1

An object of my invention is to provide a plier wrench which is an improvement over the wrench shown in my Patent No. 1,866,771, issued July 12, 1932. In the patent I show a wrench that can be used as a pipe wrench, monkey wrench or pliers due to the fact that one of the jaws has two straight object-gripping edges re-entrantly inclined to each other and the other jaw has a convex cam-shaped edge. The cam edge cooperates with the re-entrantly inclined edges so that the wrench will have a tendency to bind more tightly upon a nut or other object as more pressure is applied to the object for rotating it. It is not necessary to grip the two handles of the wrench more firmly as greater force is used for rotating the object, as is the case with the usual pliers. The cam will automatically cause the handles to tend to swing together as more force is applied to rotate the object.

In the present invention, the jaw provided with the straight edges re-entrantly inclined, has an outer straight gripping edge that makes an obtuse angle with the adjacent straight edge. The other jaw has an abutment positioned at the outer end of the cam-edge and the abutment has an edge making an obtuse angle with the cam edge and an outer straight gripping edge that cooperates with the outer straight gripping edge of the first jaw for gripping an object therebetween. The re-entrant edges on the one jaw and the abutment on the other providing sufficient space between the jaws and in back of the outer straight gripping edges to provide space for receiving a projection of the object gripped, such as the head of a cotter pin.

A further object of my invention is to provide a plier wrench that has novel means for quick adjustment for spreading the jaws to grip objects of various sizes. The quick adjusting means is designed to maintain the jaws in the same relative positions regardless of the adjustment, the only change being the greater or less spacing of the jaws one from the other.

A wire cutting means is incorporated in the plier wrench and the re-entrant edges cooperate with the cam edge for guiding the wire into the wire-receiving recesses. The plier wrench is sturdy and simple in construction.

Other objects and advantages will appear in the following specification, and the novel features of the device will be particularly pointed out in the appended claims.

My invention is illustrated in the accompanying drawings forming a part of this application, in which:

2

Figure 1 is a side elevation of the plier wrench showing the jaws gripping a hexagon nut;

Figure 2 is a transverse section taken along the line II—II of Figure 1;

Figure 3 is a side elevation of the jaws of the plier wrench showing them in a spread position for gripping a larger square nut;

Figure 4 illustrates the jaws gripping a cylindrical object;

Figure 5 illustrates the jaws gripping a cotter pin with sufficient space being provided for receiving the cotter pin head;

Figure 6 is an enlarged view of the jaws showing the wire cutting means; and

Figure 7 is a greatly enlarged view illustrating the severing of a wire by the wire cutting means.

While I have shown only the preferred form of my invention, it should be understood that various changes or modifications may be made within the scope of the appended claims without departing from the spirit and scope of the invention.

In carrying out my invention, I provide a plier wrench that has two handles A and B. The

handle A has a straight shank portion A₁ with a straight edge 1 and a slot 2 paralleling this edge. The slot has spaced notches 2a extending along the side disposed nearest the straight edge 1. Figure 2 shows the handle B carrying the

shank 3 of a pivot bolt C that pivotally connects the handles A and B together. The bolt shank 3 is rigidly secured to the handle B and is rotatably and slidably received in the slot 2. Figure 6 shows the bolt shank 3 provided with opposed flattened sides 3a that are disposed a sufficient distance apart to permit the shank to be slid along the slot 2 when the handle B is opened with respect to the handle A for bringing one of the flat sides 3a into sliding contact with the

straight edge 2b of the slot.

A four place slip joint is provided for the pivoting of the handles A and B by the bolt C and notched slot 2. In Figure 6 the bolt shank 3 has been rotated in the slot 2 for causing one of its two opposed arcuate sides 3b to contact the straight side 2b of the slot and the other arcuate side 3b to enter the adjacent notch or recess 2a. The bolt shank in this position cannot be slid along the slot 2 and the two handles A and B are pivotally connected together at the desired place along the slot. There are four notches 2a and therefore four positions into which the bolt C can be moved. The bolt has a head 4 at one end. A disc 5 is mounted on the bolt at the other end and is held in place by upsetting the projecting end of the bolt as shown at 6. The two

handles are permanently locked together by this arrangement.

The handle A carries an integral jaw D while the handle B carries an integral jaw E. The jaw D extends at an angle to the straight edge 1 of the handle shank A1. Two straight object gripping edges 7 and 8 are formed on the jaw D and are re-entrantly inclined with respect to each other. The edge 7 has teeth 7a while the edge 8 is preferably smooth. In addition to these two re-entrantly inclined edges, I provide an outer edge 9 that makes an obtuse angle with the toothed edge 7. The outer edge 9 is also provided with object-gripping teeth 9a, but these are preferably smaller in size than the teeth 7a.

The jaw E extends beyond the straight edge 1 of the handle shank A1 about the same distance as the jaw D. A convex cam edge 10 is provided on the jaw D and it cooperates with the re-entrantly inclined edges in a manner hereinafter described. The cam edge 10 extends at an obtuse angle to the handle B and it has teeth 10a of substantially the same size as the teeth 7a. An abutment E1 is positioned at the outer end of the cam edge 10 and this abutment has an inner smooth edge 11 making an obtuse angle with the cam edge 10 and an outer toothed edge 12 making an obtuse angle with the smooth edge 11. The teeth 12a on the outer abutment edge 12 are preferably of the same size as the teeth 9a and the two object-gripping edges 9 and 12 are of about the same length. Before describing the operation of the plier wrench it is best to set forth the structure of the wire cutter.

The wire cutter is shown in Figure 6 and in enlarged detail in Figure 7. The straight edge 1 has a U-shaped wire-receiving recess 13 therein with opposed edges. One of the opposed edges 13a merges into the edge 8 and constitutes one of the wire-severing edges. A cooperating wire-receiving U-shaped recess 13 at the base of the jaw E has opposed edges with the edge 14a constituting a wire-cutting edge and merging into the cam edge 10. Figure 6 shows a wire F received in the recesses 13 and 14. The handles A and B have been moved toward each other for moving the cutting edges 13a and 14a into engagement with the wire.

It will be noted from Figure 7 that as the cutting edges 13a and 14a are moved toward each other, the outer ends of these edges will pass each other before the inner ends. This results in the wire being forced to the bottoms of the recesses 13 and 14 during the severing thereof. There will be no tendency for the wire to be forced out of the recesses, but rather the wedging action of the edges 13a and 14a as they are swung about their common pivot bolt C will be to trap the wire and force it toward the bottoms of the recesses. A better cutting of the wire results.

Furthermore it will be seen that the wire can be fed into the registering recesses 13 and 14 very easily. The re-entrant edge 8 of the jaw D and the cam edge 10 of the jaw E guide the wire into the aligned recesses because the edge 8 merges into the recess edge 13a and the cam edge 10 merges into the recess edge 14a.

The abutment E1 permits the plier to ratchet on a nut without pulling loose. The abutment acting as a ratcheting retainer tends to hold the plier on the nut during the ratching movement and the edge 9 of the jaw D acts as an escape-ment edge cooperating with the edge 12 of the

abutment to permit easy entry and exit for the work entering or leaving the jaw. The inclined edge 11 of the abutment forms one of the working faces that engages with a face of a hexagon nut, see Figure 1. I do not wish to be confined to any definite number of notches 2a in the slot 2. I have shown four notches although these may be increased to five or reduced to less than four if desired.

In operating the device, the straight edge 7 of the jaw D is considered the stationary edge and the convex cam edge 10 of the swingable jaw E is considered the movable cam-shaped edge. The second and third pivot positions shown in Figures 1 and 3 are the ones most commonly used. A $\frac{1}{16}$ " hex nut is gripped by the pliers in Figure 1 and a $\frac{3}{4}$ " square nut is gripped in Figure 3. In Figures 1, 3, 4, 5 and 6, I show a dot dash line 7b coinciding with the straight edge 7 and extending to the right of the edge. I also show another dot dash line 2c extending through the center of the bolt 4 and paralleling the edge 2b of the slot 2. These two lines intersect and make an acute angle which is indicated at a. It will also be seen that the convex cam edge 10 extends almost at right angles to the line 2c when gripping an object.

It will be seen from Figures 1, 3 and 4, that the convex cam edge 10 is substantially parallel to the straight edge 7 when the two jaw edges are in object gripping position. The convex edge 10 will remain substantially the same distance away from the line 2c for all four adjustments of the pivot bolt C and therefore the jaws can grip larger objects as readily as smaller ones. Inasmuch as the convex cam edge 10 makes an obtuse angles with the length of the handle B, the edge 10 will create a camming action on the object gripped as the handle B is swung toward the handle A and will tend to wedge the object against the straight edge 7 to create a vice like grip on the object.

I claim:

1. A plier wrench having two handles with pivot means therebetween adjustable along a predetermined line; an upper jaw integral with one handle; a lower jaw integral with the other handle; the jaws projecting laterally from their respective handles, with one jaw overlying the other; the upper jaw having inner and outer straight edges reentrantly inclined relative to one another and so arranged that a line coinciding with the outer reentrant edge will form an acute angle with the line along which the pivot means is adjustable; the lower jaw having a convex cam-shaped edge so arranged that a line passing through the ends thereof will make an obtuse angle with its handle, and an abutment disposed at the outer end of this edge and projecting toward the upper jaw; the outer reentrant gripping edge of the upper jaw being disposed substantially parallel to and mating with the convex cam-shaped edge of the lower jaw regardless of the position that the pivot means occupies along the pivot means adjusting line, and while the handles are maintained in a relation with respect to each other for causing the jaws to grip an object.

2. A wrench having two jaws adjustably pivoted together and each having an integral handle; the upper jaw having inner, middle and outer straight edges; the inner and middle edges being reentrantly inclined with respect to each other and the outer edge making an obtuse angle with the middle edge and constituting an

escapement edge for an object being gripped; the lower jaw having a convex cam edge so arranged that a line passing through the ends thereof will make an obtuse angle with its handle, the lower jaw having a ratcheting retainer disposed at the outer end of the cam edge; the ratcheting retainer having an edge which approximately parallels the escapement edge on the upper jaw when the two jaws are in "ratcheting" position and which thereby provides easy entry and exit for work entering or leaving the jaws when the jaws are opened a slight distance beyond ratcheting position. 10

3. A wrench having two jaws adjustably pivoted together along a predetermined line and each having an integral handle; the upper jaw having inner, middle and outer straight edges; the inner and middle edges being reentrantly inclined and the outer edge extending approximately at right angles to the predetermined line 20 of adjustment; the lower jaw having a main curved edge so arranged that a line passing through the ends thereof will make an obtuse angle with its handle, the lower jaw having an outer edge substantially paralleling the outer 25

edge of the upper jaw when the middle straight edge of the upper jaw approximately parallels a line passing through the ends of the curved edge of the lower jaw. 5
